LATCH

Gordon E. Roedding, Grand Rapids, Mich., assignor to Grand Rapids Brass Company, Grand Rapids, Mich., a corporation of Michigan

Application September 14, 1932, Serial No. 633,095

6 Claims. (Cl. 292—226)

The present invention relates to latches for refrigerators, etc.; and its object is to provide an improved latch having a bolt-retracting handle which may be turned parallelly with the door member on which it is mounted to angularly spaced operative positions in which it may be releasably held.

This and any other and more specific objects hereinafter appearing are attained by, and the 10 invention finds preferable embodiment in, the illustrative structure particularly described in the body of this specification and illustrated by the accompanying drawing, in which:

Figure 1 is a sectional view of a door closure and door jamb and of a latch structure, taken on a plane corresponding to line 1—1 of Figures 3, 15 4 and 5;

Figure 2 is a similar view thereof but showing the parts in another position;

20 Figure 3 is a sectional view of the latch structure taken on line 3—3 of Figure 1;

Figure 4 is a sectional view of parts thereof taken on line 4—4 of Figure 1;

25 Figure 5 is a plan view of parts of said structure; and

Figure 6 is an edgewise view of the same.

In the drawing is shown a latch structure mounted on a swingable closure door member 1, its keeper or "strike" 2 being mounted on the 30 other door member, the jamb or door frame 3.

This latch structure has a latch bolt 4 desirably formed of sheet metal and pivotally mounted at 5 on the opposite sides 6 of the structure's inwardly extending sheet metal member 7 whose 35 middle portion 8 has an opening 9 through which the latch bolt projects. This member 7 is shown fastened to the inner plate 10 of the latch casing 11 by bent-over tongues 12 extending through slot openings 13 in said plate.

40 The bolt 4 is pressed into latching engagement with its keeper 2 by a coiled spring 14 surrounding a bar 15 which has a rocking movement at its ends in internal angle 16 of the bolt and on the abutment 18 of member 7, this spring pressing thereon and on the abutment 17 of the bar.

45 Means for retracting the bolt 4 from the keeper includes a handle 19 whose portion 20 is adapted to be grasped by hand. This handle is mounted for operative (bolt-retracting) movement and for 50 turning movement, parallel with the face of the closure member 1, toward angularly spaced positions in which it is thus operative and in which it is releasably held. These movements may be brought about in various ways and by various 55 mechanisms.

The specific illustrated mechanism for these purposes comprises the following:

A flat member, in form a round disk or plate 21, is mounted on the closure member 1 inside the latch casing 11 and normally is yieldingly pressed by a curved spring 24 against the casing's inner surface as seen in Figure 1, this spring at its middle bearing on the inner side of said plate (or its projecting tongue 32), its ends being secured at 37 on the plate, and between these points being bowed inwardly and bearing on the casing's inner plate 10.

5 The handle 19 has a pivot pin 25 parallel with the closure's face 22, in an open bearing 26 in plate 21, the handle thus having a swinging movement in a plane at right angles to the closure's face. Suitable motion-transmitting means operatively intermediate the handle and the bolt for retracting the same by the handle's swinging movement from the closure are provided, specific 10 means as illustrated by the drawing being the following:

15 The handle is a lever fulcrumed at 25 and has an arm 27 extending inwardly through the opening 31 in plate 21 which arm in the operative 20 swinging movement of the handle, caused by drawing its portion 20 outwardly from the closure member, engages the inner surface of a flange 28 of the bolt, which surface forms a cam bearing having a middle or bight portion 29 and 25 inclined end portions 30 as best seen in Figure 4.

20 When the handle 19 is in the turned position seen in Figure 1 the arm will engage in said bight portion, when the handle's portion 20 is swung outwardly, to retract the bolt; but when the handle is turned parallelly with the face of the closure (as hereinafter explained) about 90 degrees either way from that position, said arm will engage one or the other of the inclined portions 30 of the cam bearing to retract the bolt; and 25 if the handle be turned 180 degrees from the position seen in Figure 1 the arm 27 in such swinging movement of the handle will not engage any part of said cam bearing and therefore such 30 swinging movement of the handle will not retract the bolt.

35 The latch casing 11 has angularly spaced sockets 33, 34, 35 and 36 in any one of which the projection or tongue 32 of plate 21, when turned into registration therewith, is adapted to engage 40 45 to releasably hold this plate and the handle against turning, said plate being pressed by spring 24 into such engagement.

50 The plate 21 is released from such holding engagement by pressing the handle's portion 20 in- 55

wardly (toward the closure) so that its shoulder 38 pressing on the plate tilts the same thus inwardly on the fulcrum of its legs 23 (adjacent the plate's edge which is opposite its tongue 32) bearing on the casing's plate 10. Thus released, the plate 21 and handle may be turned parallelly with the closure's face 22 to any other angular position, the legs 23 in such turning movement sliding around on the casing's plate 10. The 10 pivot pin 25 is held in bearing 26 of plate 21, when the handle's portion 20 is drawn outwardly to retract the bolt, by the casing's front wall 40 which overhangs the plate 21.

It will be seen that the operating handle 19 15 may be turned parallelly with the face of the closure door member to opposite (vertical) positions to adapt the latch structure to closures which are hinged at their right or left hand side, and also to a (horizontal) position as may be 20 desired by the user, as well as to an opposite (horizontal) position in which the handle is inoperative to retract the bolt and thus in effect locks the closure shut.

A spring 41 coiled about the pivot pin 25 and seated in the cut-out portion 42 of the handle 25 presses its portion 20 inwardly.

The invention being intended to be pointed out in the claims, is not to be limited to or by details of construction of the particular embodiment 30 thereof illustrated by the drawing or hereinbefore described.

I claim:

1. In a latch structure including a latching bolt, means for retracting the bolt comprising: 35 a plate mounted on a door member turnable parallelly with the face of said door member toward angularly spaced operative positions of the hereinafter-mentioned handle; a handle mounted on the plate swingable in planes transverse to 40 said face and having an inwardly extending arm, the bolt having a curved bearing on which said arm bears in the swinging movement of the handle to retract the bolt.

2. In a latch structure including a latching bolt, means for retracting the bolt comprising: 45 a plate mounted on a door member turnable parallelly with the face of said door member toward angularly spaced positions, the plate being tiltable on a fulcrum on said door member in planes transverse to said face; a handle mounted on 50 the plate swingable in such transverse planes and having an inwardly extending arm engaging the bolt in the swinging movement of the handle to retract the bolt, the plate and said door member having mutually engaging parts for releasably holding the plate in turned positions, said parts being engaged and disengaged by the tilting movements of the plate.

3. In a latch structure including a latching bolt, means for retracting the bolt comprising: a plate mounted on a door member turnable parallelly with the face of said door member toward angularly spaced positions, the plate being 5 10 tiltable against spring-pressure on a fulcrum on said door member in planes transverse to said face; a handle mounted on the plate swingable in such transverse planes and having an inwardly extending arm engaging the bolt in the swinging 15 movement of the handle to retract the bolt, the plate and said door member having mutually engaging parts for releasably holding the plate in turned positions, said parts being engaged and disengaged by the tilting movements of the plate. 15

4. In a latch structure including a latching bolt, means for retracting the bolt comprising: a plate mounted on a door member turnable parallelly with the face of said door member toward operative positions of the hereinafter-mentioned 20 handle and toward an inoperative position thereof and tiltable inwardly on a fulcrum on said door member in planes transverse to said face; a handle mounted on the plate swingable outwardly in such transverse planes and having an inwardly 25 extending arm, the bolt having a cam bearing including a bight portion and inclined end portions on which said arm bears in the outwardly swinging operative movement of the handle to retract the bolt, the plate and said door member having 30 mutually engaging parts for releasably holding the plate in turned positions, the plate being tiltable inwardly by the inwardly swinging movement of the handle to disengage said parts.

5. In a latch structure including a latching 35 bolt, means for retracting the bolt comprising: a handle carried by a door member swingable in a plane transverse to the face of said member and having an inwardly extending arm, the bolt having a curved bearing on which said arm bears in 40 the swinging movement of the handle to retract the bolt, the handle having also a turning movement parallel with said face toward angularly spaced operative positions.

6. In a latch structure including a latching bolt, means for retracting the bolt comprising: a handle carried by a door member swingable in a plane transverse to the face of said member and having an inwardly extending arm, the bolt 50 having a cam bearing including a bight portion and inclined end portions on which said arm bears in the swinging movement of the handle to retract the bolt, the handle having also a turning movement parallel with said face toward 55 angularly spaced operative positions.

GORDON E. ROEDDING.
